CLAIM

The ornamental design for a battery as shown and described.

DESCRIPTION

FIG. 1 is a first perspective view of a battery; FIG. 2 is a second perspective view thereof; FIG. 3 is a front view thereof; FIG. 4 is a rear view thereof; FIG. 5 is a left side view thereof; FIG. 6 is a right side view thereof; and, FIG. 7 is a top view thereof.

Broken lines in the drawings are for the purpose of illustrating portions of the battery that form no part of the claimed design.

1 Claim, 7 Drawing Sheets
